Primary Examiner — Mary Ann Calabrese*Assistant Examiner* — Jennifer L Rempfer(74) Attorney, Agent, or Firm — Nicholas A. Kees; Godfrey & Kahn, S.C.(57) CLAIM

The ornamental design for a football infant bodysuit, as shown and described.

DESCRIPTION

FIG. 1 is an isometric view of a football infant bodysuit, showing one embodiment of my new design;

FIG. 2 is a front view thereof;

FIG. 3 is a rear view thereof;

FIG. 4 is a side view thereof, with the opposite side view being a mirror image thereof;

FIG. 5 is a top plan view thereof; and,

FIG. 6 is a bottom plan view thereof.

The features shown in broken lines in the various drawing figures are used to show environmental structure, and form no part of the invention.

1 Claim, 4 Drawing Sheets(56)
